(57) **CLAIM**

The ornamental design for a gear shift knob, as shown and described.

DESCRIPTION

FIG. 1 is a perspective view of a gear shift knob according to the present application.

FIG. 2 is a side view of the gear shift knob of FIG. 1.

FIG. 3 is a top view of the gear shift knob of FIG. 1.

FIG. 4 is a bottom view of the gear shift knob of FIG. 1.

FIG. 5 is an exploded perspective view of the gear shift knob of FIG. 1.

FIG. 6 is an alternate perspective view of the gear shift knob of FIG. 1.

FIG. 7 is a perspective view of a cap member of the gear shift knob of FIG. 1.

FIG. 8 is a side view of the cap member of FIG. 7.

FIG. 9 is a top view of the cap member of FIG. 7.

FIG. 10 is a bottom view of the cap member of FIG. 7.

FIG. 11 is a perspective view of a base member of the gear shift knob of FIG. 1.

FIG. 12 is a right side view of the base member of FIG. 11.

FIG. 13 is a left side view of the base member of FIG. 11.

FIG. 14 is a front view of the base member of FIG. 11.

FIG. 15 is a back view of the base member of FIG. 11.

FIG. 16 is a top view of the base member of FIG. 11; and,

FIG. 17 is a bottom view of the base member of FIG. 11. The broken lines are included for the purpose of illustrating environmental structure and form no part of the claimed design.

1 Claim, 11 Drawing Sheets
